UNITED STATES PATENT OFFICE

165,772

BUILDING MOUNTED COMBINATION AIR INTAKE AND EXHAUST VENT FOR HEATERS

Allan W. Lundstrum, Carmel, Ind.

Application May 4, 1950, Serial No. 9,693

Term of patent 14 years

(Cl. D81—1)

To all whom it may concern:

Be it known that I, Allan W. Lundstrum, a citizen of the United States, residing at Carmel, in the county of Hamilton and State of Indiana, have invented a new, original, and ornamental Design for a Building Mounted Combination Air Intake and Exhaust Vent for Heaters, of which the following is a specification, reference being had to the accompanying drawings, forming part thereof.

Fig. 1 is a perspective view of a building mounted combination air intake and exhaust vent for heaters, showing my new design;

Fig. 2 is a side elevational view thereof; and

Fig. 3 is a plan view thereof.

The other side is like the side shown in Fig. 2.

The dominant features of my design reside in the portions shown in full lines.

I claim:

The ornamental design for a building mounted combination air intake and exhaust vent for heaters, as shown and described.

ALLAN W. LUNDSTRUM.
